United States Patent

Des. 237,378
Patented Oct. 28, 1975

237,378

LODGE

Kenji Ekuan, 308, 1-chome, Kamishakujii, Nerima-ku
Tokyo, Japan

Filed Feb. 12, 1973, Ser. No. 331,873

Term of patent 14 years

Int. Cl. D25—03

U.S. Cl. D13—1 R

FIG. 1

FIG. 6

FIG. 7

FIG.2

FIG.3

FIG. 4

FIG. 5

FIG. 1 is a perspective view of a lodge, showing the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view taken from the left of FIG. 1; and

FIG. 7 is a side elevational view taken from the right of FIG. 1.

I claim:

The ornamental design for a lodge, as shown.
